United States Patent

Des. 240,683
Patented July 27, 1976

240,683

COMBINED AIR CIRCULATOR AND ROOM DIVIDER

Don A. Taylor, 216 Mills St.,
Wadsworth, Ohio 44281

Filed Dec. 30, 1974, Ser. No. 537,790

Term of patent 14 years

Int. Cl. D6—06; D23—04

U.S. Cl. D6—139

FIG. 3

FIG. 4

FIG. 1

FIG. 2

FIG. 1 is a front elevational view of a combined air circulator and room divider showing my new design, the rear view being a mirror image thereof;

FIG. 2 is a left side elevational view, the right side being a mirror image thereof;

FIG. 3 is a top plan view; and

FIG. 4 is a bottom plan view.

I claim:

The ornamental design for a combined air circulator and room divider, as shown and described.
